(57) **CLAIM**

The ornamental design for an image device for projecting floating images in the air, as shown and described.

DESCRIPTION

FIG. 1 is a front and right side perspective view of an image device for projecting floating images in the air showing our new design;

FIG. 2 is a rear and right perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

Portions of the image device for projecting floating images in the air shown in broken lines in FIGS. 3, 4 and 8 form no part of the claimed design.
